(57) **CLAIM**

I claim the ornamental design for a terminal configuration of a six contact female connector, as shown and described.

DESCRIPTION

FIG. 1 is a perspective view of the terminal configuration of a six contact female connector of the present invention; FIG. 2 is a front elevational view of the terminal configuration of a six contact female connector of the present invention;

FIG. 3 is a back elevational view of the terminal configuration of a six contact female connector of the present invention;

FIG. 4 is a left side view of the terminal configuration of a six contact female connector of the present invention;

FIG. 5 is a right side view of the terminal configuration of a six contact female connector of the present invention; and, FIG. 6 is a bottom side view of the terminal configuration of a six contact female connector of the present invention.

The broken lines depicting the connector housing and the conductors are included for the purpose of illustrating environmental structure only and form no part of the claimed design.
